VANITY BOX

Eldon D. Motz, North Canton, Ohio

Application June 9, 1939, Serial No. 278,341

4 Claims. (Cl. 132—83)

The present invention relates to new and useful improvements in vanity boxes and has for its primary object to provide, in a manner as hereinafter set forth, a device of this character embodying novel illuminating means whereby said device may be conveniently used in the dark.

Another important object of the invention is to provide a vanity box of the aforementioned character including powder and rouge containers of a unique construction and arrangement.

Other objects of the invention are to provide a vanity box of the character set forth which will be comparatively simple in construction, strong, durable, highly efficient and reliable in use, compact, light in weight, attractive in appearance and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is a perspective view of a vanity box constructed in accordance with the present invention, showing the device open.

Figure 2 is a view in vertical section through the vanity box, showing the device closed.

Figure 3 is a vertical sectional view, taken substantially on the line 3—3 of Fig. 2.

Figure 4 is a fragmentary view in vertical section through the lower portion of the invention, showing the device open.

Figure 5 is a view in horizontal section, taken substantially on the line 5—5 of Fig. 2.

Figure 6 is a detail view in perspective of the lipstick holder.

Referring now to the drawings in detail, it will be seen that the embodiment of the invention which has been illustrated comprises a vertically elongated case of any suitable material which is designated generally by the reference numeral 1. The front of the case 1 is open and is adapted to be closed by a closure 2 which is hinged to the bottom 3 of said case, as at 4. A brace or link 5 supports the closure 2 in a substantially horizontal position when open. A latch 6 is provided on the free end of the closure 2 for releasably securing said closure in closed position.

The case 1 is divided into upper and lower compartments 7 and 8, respectively, by a horizontal partition 9. Mounted in the front of the upper compartment 7 is a mirror 10 having an unsilvered upper portion providing a window 11

(see Fig. 1) the purpose of which will be presently set forth.

The reference numeral 12 designates a removable top which is insertable in the upper portion of the case 1. Depending from the rear of the top 12 is a plate 13. Removably mounted on the plate 13 is a dry cell battery 14. Also mounted on the plate 13 is a socket 15 for the reception of an electric light bulb 16. The socket 15 is electrically connected with the dry cell battery 14. Mounted on one side of the case 1 is a suitable switch 17 which is engageable with a dry cell battery 14 for controlling the electric light bulb 16. It will be observed that the light bulb 16 is positioned adjacent the window 11 and an opening 18 in the top 12.

Fixed on the closure 2 is a powder container 19 comprising a hinged closure 20, said powder container being positioned in the lower chamber 8 when the closure 2 is closed. The cover 20 of the powder container 19 has formed therein a circular recess or well 21 for the reception of a removable rouge container 22 which is provided with a hinged cover 23.

The reference numeral 24 designates a lipstick holder in the form of a substantially V-shaped spring, one leg of which is fixed on the closure 2. On the free end portion of the other leg of the substantially V-shaped resilient holder 24 is a clip 25 which is adapted to clamp a conventional lipstick tube 26 in position.

It is thought that the manner in which the device functions will be readily apparent from a consideration of the foregoing. When the closure 2 is swung downwardly to open position the mirror 10 is exposed and the containers 19 and 22 and the lipstick 26 are brought into position for convenient use. This is shown to advantage in Fig. 1 of the drawings. If light is desired, the switch 17 is simply closed for lighting the electric bulb 16. The face of the user is then illuminated through the window 11. The opening 18 adjacent the electric light 16 adapts the device for use as a flashlight. By simply removing the top 12 from the case 1 the battery 14, the electric light bulb 16, etc., are withdrawn from the upper compartment 7. This, of course, facilitates replacement. The holder 24 supports the tube 26 in position to facilitate the removal and replacement of the lipstick. Also, when the closure 2 is closed the lipstick tube 23 is adapted to engage the back wall 27 in a manner to put the resilient holder 24 under tension. Thus, the holder 24 also constitutes means for opening the closure 2 when the latch 6 is released. Further, by shifting the

lipstick tube 26 longitudinally in the clip 25 the tension under which the holder 24 will be placed when the closure 2 is closed may be regulated as desired. Of course, the tube 26 may be expeditiously removed from the holder 24 for replacement when the lipstick therein has been exhausted. Also, the rouge container 22 may be conveniently removed from the recess or well 21 when desired.

It is believed that the many advantages of a vanity box constructed in accordance with the present invention will be readily understood and although a preferred embodiment of the device is as illustrated and described, it is to be understood that changes in the details of construction and in the combination and arrangement of parts may be resorted to which will fall within the scope of the invention as claimed.

What is claimed is:

- 20 1. A vanity box comprising a case open at its front, a mirror mounted in the front portion of the case, a removable top insertable in the upper portion of the case, a plate depending from the rear portion of the top, and an electric lamp mounted on said plate, the mirror having a window therein for the passage of light from the electric lamp and the removable top having an opening therein adjacent the lamp for the passage of light therefrom.
- 25 2. A vanity box comprising a case open at its front, a hingedly mounted closure for the front of

the case, a horizontal partition in said case providing upper and lower compartments, a mirror in the front portion of the upper compartment, a removable top for the case insertable in the upper compartment, a plate depending from the rear portion of said top, a battery mounted on said plate, an electric lamp mounted on the plate and electrically connected with said battery, the mirror having a window therein for the passage of light from the lamp, and a container fixed 10 on the closure and engageable in the lower compartment when said closure is in closed position.

3. A vanity box comprising a case, a closure hingedly mounted on said case, a container fixed on the inner side of said closure and engageable 15 in the case when the closure is in closed position, said container comprising a cover including a well, and a container removably mounted in said well.

4. A vanity box comprising a case, a closure 20 hingedly mounted on said case, a substantially V-shaped resilient holder mounted on said closure, a clip on said holder, and a tube for the reception of a lipstick removably and adjustably mounted in the clip, said tube being engageable 25 with the case for tensioning the resilient holder when the closure is in closed position, said resilient holder constituting means for swinging the closure to open position.
